His Attest.

UNITED STATES PATENT OFFICE.

HENRY J. HUBERT, OF ST. LOUIS, MISSOURI, ASSIGNOR TO JOHN T. MILLIKEN, OF ST. LOUIS, MISSOURI; NATIONAL BANK OF COMMERCE IN ST. LOUIS, JOHN G. LONSDALE, AND H. W. LOEB EXECUTORS OF SAID JOHN T. MILLIKEN, DECEASED.

CAPSULE-MACHINE.

1,302,372.

Specification of Letters Patent. Patented Apr. 29, 1919.

Application filed October 1, 1917. Serial No. 194,296.

To all whom it may concern:

Be it known that I, HENRY J. HUBERT, a citizen of the United States, and a resident of the city of St. Louis and State of Missouri, have invented a new and useful Improvement in Capsule-Machines, of which the following is a specification.

This invention relates to capsule machines, and more particularly to that portion of such machines where the finished body and cap halves of the capsules are joined together, as by telescoping the one within the other, prior to being discharged from the machine.

It has more particularly to do with the joiner-bar construction by itself, the object being to produce an improved joiner-bar which will afford compensation for considerable variation in the diameters of the capsule shells and accurately position them in telescoping relation so as to facilitate the assembling of the cap and body sections of the capsules, thereby avoiding waste and damage to the mechanism of the machine, such as has heretofore occurred, due to the jamming of the capsule sections which were not brought into accurate juxtaposition for telescoping. A further object is to produce a structure which may be readily substituted for that heretofore employed in machines of this character, without necessitating any material alteration in the balance of the mechanism. Other objects and advantages to be attained will hereinafter more fully appear.

In the accompanying drawings illustrating a practical adaptation of the invention,—

Figure 1 is a fragmentary view, partly in top plan and partly in horizontal section, of the joiner-bar and so much of the machine as co-operates directly therewith; Fig. 2 is a vertical section on the line 2—2 of Fig. 1, the cap and body holders being shown as actuated to join the two sections of the capsule;

Fig. 3 is a similar view, the cap and body holders being shown in their receiving positions, and the joiner-bar turned to receive the ejector which discharges the capsule;

Fig. 4 is a face view and section of the joiner-bar, at right angles to that shown in Fig. 1, showing the split bushing in end

view, and in cross section on the lines 4—4 of Fig. 1; and

Fig. 5 is an end view of the sections of the split bushing and the resilient split retaining ring detached.

Referring now to the drawings, the joiner-bar is indicated by the numeral 1. Only a fragment of this bar is shown, as it is the same throughout its length. In practice, it is provided at its ends with bearings 2, which are journaled in the frame of the machine (not shown). In the machine, which is of the usual or well-known construction and arrangement, this bar is given an intermittent rocking or oscillating movement, approximately a quarter turn, or more or less, as the case may be, according to the relative arrangement of the co-operating parts of the machine.

At intervals throughout its length, the bar 1 is provided with transverse, parallel bores 3. As shown, these bores are of two diameters, and mounted loosely therein are expandible bushings 4. These bushings, as shown, externally, are counterparts of the bores 3, but of considerably smaller diameter, so as to permit expansion, and they are preferably made in three sections or segments (see Fig. 5). They are retained in the bores, with limited endwise movement to prevent binding, by a perforated plate 5, the openings 6 of the latter being slightly larger in diameter than the reduced end portions 7 of the bushings. In the larger portion of the bushing, and approximately midway between its ends, is an annular circumferential groove in which a split resilient ring 8 is placed, whereby the sections of the bushing are yieldably held in normally closed relation.

From one end the bushing 4 has a bore 9 corresponding to the desired minimum diameter of the capsule body half, and from its opposite end it has a bore 10 corresponding likewise to the desired diameter of the cap half of the capsule, there being a slight abrupt shoulder 11 at the meeting inner ends of the two bores. The outer end portions of the two bores are flared, as at 12, so as to guide the capsule sections into the respective bores in the bushing if not presented thereto in exact alinement.

Pivots mounted at opposite sides of

the joiner-bar are the usual carriers 13 for the shell-holders 14 and 15 for the body and cap halves of the capsule, respectively. These carriers are intermittently oscillated, 5 through mechanism not shown, but obvious and well-known in the art, to receiving position with relation to the feeders 16 (see Fig. 3), and to the joiner-bar 1 (see Figs. 1 and 2). The holders 14 and 15 have the 10 usual recessed ends providing seats for the rounded, closed ends of the respective capsule sections, and they have small axial bores 17 for connection with a suction device (not shown), whereby the capsule sections are held on the members 14 and 15, until the latter are moved into cooperative relation to the joiner-bar and then moved endwise to force the capsule sections into the bushings 4. After the capsule sections 15 have entered the bushings, and just prior to the completion of the inward stroke of the members 14 and 15, they are relieved of the suction.

In the operation of the machine, the member 15 is actuated before the member 14, so that the cap half of the capsule is first brought into the bushing 4 against the shoulder 11, and then the member 14 pushes the body half of the capsule through the bore 9 and telescopes it with the cap half.

The construction and arrangement of the split bushing 4 is such that it assures the proper alignment of the capsule sections to facilitate the telescoping thereof, and it is 35 yieldable to compensate for variation in the diameters of the respective shells.

After the capsule is joined, as shown in Fig. 2, the members 14 and 15 are withdrawn and turned to receive another charge, 40 as shown in Fig. 3. At the same time, the joiner-bar 1 is given a quarter turn into cooperative relation to an ejector 18 which is in turn reciprocated through the bushing 4 to discharge the capsule therefrom.

As the parts of the machine other than the joiner-bar are of the usual and well-known construction and arrangement, it is deemed unnecessary to illustrate them completely in the drawings. Therefore, only 45 such parts that cooperate directly with the joiner-bar are illustrated fragmentarily or schematically. It is also obvious that the joiner-bar and expansible bushings admit of considerable modification without departing from the spirit of the invention as defined by the appended claims. Therefore, it is not limited to the specific construction and arrangement shown.

What is claimed is:

60 1. In a capsule machine, a joiner device comprising an expansible bushing having concentric bores of different diameters adapted respectively for the reception of the cap and body halves of the capsule in telescopic relation, said bushing comprising

radially movable sections and means for yieldingly holding them together.

2. In a capsule machine, a joiner device comprising a bar having a transverse bore therethrough, and an expansible bushing 70 mounted loosely in said bore having concentric bores of different diameters adapted respectively for the reception of the cap and body halves of the capsule in telescopic relation, said bushing comprising radially 75 movable sections and means for yieldingly holding them together.

3. In a capsule machine, a joiner device comprising a bar having a transverse bore therethrough, and an expansible bushing 80 mounted loosely in said bore, said bushing having an axial bore from one end corresponding to the cap half of the capsule and a similar bore from its opposite end corresponding to the body half of the capsule, 85 and an annular shoulder at the meeting inner ends of said axial bores, the outer end portions of said axial bores being flared, said bushing comprising radially movable sections and means for yieldingly holding 90 them together.

4. In a capsule machine, a joiner device comprising a bushing split longitudinally to provide separable segmental sections, and resilient means for yieldably holding said 95 segmental sections in normally closed relation, said bushing having concentric bores of different diameters adapted respectively to fit the cap and body halves of the capsule.

5. In a capsule machine, a joiner device comprising a bushing split longitudinally to provide separable segmental sections, and resilient means for yieldably holding said 100 segmental sections in normally closed relation, said bushing having an axial bore from one end corresponding to the cap half of the capsule and a similar bore from its opposite end corresponding to the body half of the capsule, and an annular shoulder at the meeting inner ends of said axial bores, the outer end portions of said axial bores being flared.

6. In a capsule machine, a joiner device comprising a bar having a transverse bore 115 therethrough and of two diameters, and a bushing mounted in said bore, said bushing being, externally, a counterpart of said bore, but of smaller diameter, said bushing being split longitudinally to provide separable 120 segmental sections and having an annular circumferential groove therein, a split resilient ring mounted in said groove so as to yieldably hold said segmental sections in normally closed relation, and means for retaining said bushing in the bore of said bar with limited endwise movement, said bushing having an axial bore from one end corresponding to the cap half of the capsule and a similar bore from its opposite end 125 130

corresponding to the body half of the capsule, and an annular shoulder at the meeting inner end portions of said axial bores, the outer end portions of said axial bores being 5 flared.

7. In a capsule machine, in combination with the usual carriers for the cap and body halves of the capsule, and the ejector for the joined capsule, a joiner device comprising a 10 bar movable to coöperate with said carriers and said ejector, said bar having an expandible bushing for the reception of the cap and body halves of the capsule in telescopic relation, said bushing comprising 15 radially movable sections and means for yieldingly holding them together.

8. In a capsule machine, an oscillatory joiner-bar, carriers for the cap and body halves of the capsule, respectively operat-

ing on opposite sides of said joiner-bar, and 20 an ejector operating in coöoperative relation to said joiner-bar to discharge the joined capsule, said joiner-bar having a transverse bore therethrough, and a bushing mounted loosely in said bore, said bushing being split 25 longitudinally to provide separable segmental sections, and having an axial bore from one end corresponding to the cap half of the capsule and a similar bore from its opposite end corresponding to the body half 30 of the capsule, an annular shoulder at the meeting inner ends of said axial bores, and resilient means for yieldably holding said segmental sections in normally closed relation. 35

Signed at St. Louis, Missouri, this 29th day of September, 1917.

HENRY J. HUBERT.
